WIRE CONNECTOR

Martin D. Bergan, Westfield, N. J., assignor to
 The Thomas & Betts Co., Elizabeth, N. J., a corporation of New Jersey

Application February 9, 1940, Serial No. 318,038

2 Claims. (Cl. 173—269)

The invention relates to a wire connector of the type commonly called a "bonding jumper." A jumper usually includes a pre-selected length of wire or cable at each end of which there is joined a terminal means having a screw hole or other means to be used for securing the jumper in service position with some other structure.

An object of the invention is to produce a wire connector having a new electrical terminal member in the form of a stepped-size tubular lug which is specially formed in combination with a stranded flexible wire conductor, wherein said wire strands are reinforced and supported in a new manner within said terminal member and so arranged as not only to resist breakage where the conductor joins the member but likewise the latter has a wider terminal end than usual, thereby adapting it to be pierced with a large hole, without impairing its strength, for the reception of a standard bolt or screw by which a large-area contact and more rugged connection are established with a bus bar or other structure and parts requiring electrically bonded connections.

Other objects of the invention will be more apparent from the following description taken in connection with the accompanying drawing, illustrating a preferred embodiment of the invention, in which:

Figure 1 is a view of the separate parts of the wire connector or bonding jumper before assembly with each terminal tube in position ready to be slipped over its respective end of the wire strands.

Figure 2 is a view showing each terminal tube slipped over its respective end of the wire.

Figure 3 is an end view of the jumper as far as it is completed as shown in Figure 2.

Figure 4 shows the bonding jumper with the larger ends of each terminal tube pressed or mashed together to form a wide area terminal means adapted to receive a screw or bolt of standard size.

Figure 5 is a side view of the bonding jumper of Figure 4, constituting a new combination of terminal lug and stranded conductor.

Figure 6 shows the completed bonding jumper with the projecting ends of the strands of the wire trimmed off.

Figure 7 is a section through one of the terminal means of the bonding jumper secured in position by a terminal screw and resisting the crushing effect of the screw head, as well as supporting the wire strands against breakage where they join to the terminal member.

The wire connector or bonding jumper utilizes

10 a terminal means or part which is initially a tube or tubular lug piece 10 having a large diameter 11 at one end or length thereof and a small diameter 12 at the other end or length thereof, thus forming a tubular lug of stepped size. The small diameter end of the tubular piece has a wire bore 13 which approximates the diameter of the stranded wire or cable 14 so that the end of the wire may be easily received therein with a close or snug fit.

15 The tubular piece may be formed in any suitable manner. For example, a small tube or pipe may be selected having a diameter which corresponds with the desired diameter for the small end 12 of a terminal means for receiving the end of wire 14, and this small tube then has one end enlarged to the desired large diameter end 11. Again, a tube may be selected having the desired large diameter and one end thereof is then 20 swaged to the desired small diameter to form the terminal means. A third method is to use a tube of intermediate diameter and enlarge one end or length 11 to the proper large diameter and swage the other end or length 12 to the desired small diameter to fit the wire to be received therein. These methods particularly described produce a seamless terminal tube.

25 A terminal tube or tubular lug piece of stepped size, that is, two diameters in this instance, is slipped over each end of the wire 14 with the larger diameter at the outer ends. The wire preferably projects slightly beyond the ends of the tubular piece as shown in Figure 2. This is merely to assure that the entire flattened end or 30 length of the terminal means will grip the wire. The wire strands 14 have a close fit in the small tubular end 12 and initially a loose fit in the large tubular end 11.

35 The smaller diameter end 12 of the terminal tube may, if desired, be given an indentation or crimping 17 for preliminarily securing the same to the wire. The larger diameter end of the terminal tube is then flattened from its outer end back to a flattening line 19 extending across its conic portion and simultaneously the end of the wire or cable 14 is also flattened. The strands spread out within the flattened end 21 for completely and uniformly filling same and are firmly gripped therein. Consequently, the flattened out strands of the wire will extend the entire width 40 of the flattened interior.

45 Means are provided to secure the terminal means to some other structure, such as a hole 18 which may be drilled, punched, or otherwise provided in the flattened end or portion, thereby

transforming the terminal tube into a terminal means. The ends of the strands of wire projecting from the flattened end of the terminal means may be trimmed even with the end thereof to leave a neat appearing bonding jumper.

Usually a bonding jumper or jumper wire includes a predetermined length of wire with a terminal means at each end thereof. It is to be understood, however, that the jumper wire may have a terminal piece, as described, at one end only, and the other end may have no terminal means whatever. It is also clear that the jumper wire may have a terminal means at one end, as described herein, and the other end may have a terminal means of any other suitable construction.

In the method of forming the terminal piece upon the end of the wire, the larger diameter end of the tubular piece 10 may be flattened in any suitable way such as by mashing it between the jaws of a punch press, or it may be flattened by passing it a desired distance between rollers so that in the latter case the larger diameter end is rolled flat. Whichever method is used for flattening the larger diameter end, it is desirable, although not essential, that one of the flattened faces 20 be tangent with, or approximately tangent with, the outer surface of the small diameter end 12 as illustrated in Figures 5 and 7.

This new terminal satisfactorily combines with stranded wire by which to produce rugged electrical bonding jumpers for all manner of grounding installations and wiring work. This new combination stranded conductor and terminal lug endures against vibrational strain and hard service, and the wire 14 is not likely to crystallize and break from or at the tubular lug 10.

Such improvement in function, with resulting prolonged life, is attained by reason of the fact that the small tubular end or length 12 envelopes the wire strands for a distance back from the large flattened end or length 11, that is, for a distance back from the transverse flattening line 19 (Figure 4) defining the terminus of the flat area. The small tube length 12, which snugly (though not tightly) embraces and reinforces the wire strands against vibration, insures against eventual crystallization and prevents rupture of the strands in whole or part.

The juncture of the small length 12 with the large length 11 of the tubular contact 10 is integrally formed through a conically-shaped portion serving to step-up the tubing from small to large size. Thus the conic formation, substantially centrally located in the tube 10, receives the flattening tool or press, thus disposing the flattening or swaging crimp line 19 transversely across or through the cone. The result is that the transverse pinch or crimp line is localized across or through the juncture cone and disposed far back from the outer extremity of the small tube 12.

Another characteristic feature resides in the fact that a certain amount of annular clearance initially exists between the wire 14 and the inside tubular wall before the line 19 (Figure 4) of flattening pressure is applied. This annular clearance within the tapering or conic portion allows the two-stage diameter tube to be deformed by pressure without cutting or forming a break line or seam across the tube. It is to be seen that the tube initially yields under the flattening pressure and has room or annular space around

the wire to permit a partial flattening before the tube walls begin to squeeze the wire in the region of the swaging or flattening line 19. The delicate wire strands are preserved against a shearing tendency, although subjected to the heavy swaging and flattening tool used in reducing the terminals to the characteristic formation shown.

It follows therefore, that the delicate strands 14 cannot vibrate or move at the transverse crimping or pressure line, which is the critical point where prior art devices are subject to rupture. This invention is found to solve the problem by not only locating the critical pressure line 19 so as to support the wire strands at a point remotely from the pressed area of the terminal but likewise has the advantage of a wide terminal end.

Regarding the last named feature, the size of the larger tube length 11 being comparatively larger than the other length 12, provides a wide-area terminal end 21 when it is flattened. The width of this flattened end 21 is greater than conventional terminal pieces, for given sizes of terminal material, and thus is afforded adequate material or stock through which to punch a full size hole 18. Consequently, a larger bolt or screw can be used which results in a more rugged electrical connection with a bus bar or the like. The centrally disposed conic-portion provides these several advantages and the wide end with larger size screw hole affords a maximum of electrical contact area between the terminal and bus bar with which it is connected.

This invention is presented to fill a need for a new and useful wire connector. It is understood that various modifications in construction, operation, use and method, may and often do occur to those skilled in the art, especially after benefiting from the teachings of an invention, and that this disclosure with its appended claims are descriptive of the principles but not limited to the illustrated embodiment of the invention.

What is claimed is:

1. An electrical wiring connector comprising, in combination, a tubular terminal of stepped-size formation providing two lengths of different diameters, thereby constituting small and large tubular lengths merging integrally through a conically-shaped portion substantially intermediate the extremities of the terminal, and a stranded wire conductor mounted with a snug fit in the small tubular length and extended into the large tubular length with a loose fit, the wire strand extremities being made substantially flush with the extremity of the large tubular length, and the large tubular length being reduced by pressure to form a wide flattened end with the wire strands spreading out from side to side therein, the resultant pressure on the wide flattened end establishing an anchorage and positive electrical connection with the wire strands, the pressure aforesaid also producing a flattening line extending across the conically-shaped portion substantially transversely of its axis, whereby the wire strands are supported by the small tubular length to endure vibration by restraining said strands against bending motion at the flattening line.

2. An electrical wiring connector comprising, in combination, a tubular terminal member of stepped-size formation having two tubular lengths of different diameters, thus providing

small and large tubular lengths merging integrally through a conically-shaped portion disposed between the extremities of the member, and a stranded wire flexible conductor mounted with a snugly supporting fit in the small tubular length and extended into the large tubular length with a loose fit, the large tubular length and the loose wire strands therein being reduced by pressure to form a flattened terminal end and to establish an anchorage as well as a positive electrical connection with the wire strands, the pressure aforesaid also producing a flattening

5 line extending across the conically-shaped portion transversely of its axis, the flattened terminal end being of substantial width and area by reason of its initial diameter being comparatively greater than the other tubular length, thereby affording adequate stock for a substantially large perforation punched through it for the reception of screw means adapted for use in anchoring the terminal end, with its large-area contact, against a bus bar or the like.

MARTIN D. BERGAN.
